UNITED STATES PATENT OFFICE.

FRANCESCO CIRELLI, OF PHILADELPHIA, PENNSYLVANIA.

SOUND-REPRODUCING MACHINE.

1,357,381.

Specification of Letters Patent.

Patented Nov. 2, 1920.

Application filed May 23, 1919. Serial No. 299,153.

To all whom it may concern:

Be it known that I, FRANCESCO CIRELLI, a subject of the King of Italy, residing at Philadelphia, in the county of Philadelphia and State of Pennsylvania, have invented 5 certain new and useful Improvements in Sound-Reproducing Machines, of which the following is a specification.

One object of my invention is to provide 10 a neat and compact sound reproducing machine which will give out a great volume of reproduced sound and which will include means so arranged that it can be readily adjusted to cause the reproduced sound to 15 be deflected in various directions.

Another object is to so construct my invention that it will include portions so arranged that any imperfections due to an irregular or wavy surface of the record will 20 not affect the proper rendition of the record.

Another object is to provide means whereby when the machine is playing, a hose or tube connected thereto can be led into a room or other place remote from the machine 25 so that persons can hear the playing of the machine through the tube.

A still further object is to make my improved machine in such manner that certain of the elements can be readily taken 30 apart so as to be stored in a comparatively small space and as such can be readily adapted as a portable machine since the removable elements can be stored in a cabinet which can be easily carried.

Another object is to make my invention 35 of a simple and durable construction and so that it can be manufactured and sold at a reasonably low cost.

These objects, and other advantageous 40 ends which will be described hereinafter, I attain in the following manner, reference being had to the accompanying drawings in which—

Figure 1 is a top plan view of a machine 45 constructed in accordance with my invention,

Fig. 2 is a side elevation of my improved machine showing certain of the parts illustrated in section,

Fig. 3 is a front elevation of my improved machine,

Fig. 4 is a fragmentary side elevation showing a different position of the horn from that shown in Fig. 2,

Fig. 5 is a fragmentary detached perspective view of certain of the elements of my invention. 55

Figs. 6 and 7 are front end elevations showing different positions of certain of the elements of my invention, 60

Fig. 8 is an enlarged fragmentary sectional view taken on the line 8—8 of Fig. 1,

Fig. 9 is a fragmentary detached perspective view of a portion of the sound box and a portion of one of the horns, and 65

Fig. 10 is a fragmentary plan view partly in section showing how the hose can be coupled so as to conduct reproduced sound to a position remote from the machine. 70

Referring to the drawings, 12 represents a cabinet which can be of any of the usual constructions including a motor (not illustrated) and a turntable 13 which is rotatably mounted on the cabinet and driven by the motor. A lid 14 is hinged at 15 to the cabinet 12 and has a plate 16 secured thereto in which is screwed a standard 17. The standard 17, when the lid 14 is open, provides a bearing for a pivot post 18, said post being adapted to be freely inserted within or removed from the standard 17. The post 18 has an arm 19 and said arm either can be made solid or hollow and merely acts as a supporting member as will hereinafter be described. A block 20 which is preferably made hollow and open at its end, as shown at 21 (Fig. 8), is hinged at 22 to the arm 19. The front end 23 of the block 20 is closed and a pivot bolt 24 extends through and is secured to the end 23. An elongated hollow head 25 is pivotally mounted on the bolt 24 so as to be free to swing; said pivot bolt 24 being located substantially midway between the ends of said hollow head. The block 20 has a cup-shape housing 26 which is open at its front end and into this housing extends a pin 27, said pin being secured to the top of the elongated head 25 by screws 28. The pin 27 is of smaller width than the internal width of the housing 26 so that the head 25 is permitted to swing to the extent of the difference in width between the pin 27 and the interior of the housing 26, as clearly 75

shown in Figs. 6 and 7. 80

The head 25 includes cylindrical end portions 29 and 30 and each of these end portions includes two bayonet slots 31 and 32; the slots 31 being normally positioned at 85

90

95

100

105

the extreme top, while the slots 32 are positioned below the level of the slots 31, for a purpose hereinafter to be described. The head 25 has an opening 33 in its front end, 5 said opening being surrounded by a flange 34. A cap 35 normally fits the flange 34 and closes the opening 33.

A double sound box 36 includes two rings 37 and 38 which are spaced apart by spacing blocks 39 and 40. The rings 37 and 38 respectively support diaphragms 41 and 42. These diaphragms are separately connected by arms 43 and 44 to a common stylus head 45, said stylus head having a single 15 needle holder 46 thereon, adapted to secure the needle 47 which operates on the record 48 which is placed on the turntable 13, in the usual manner. The ring 37 has a tubular extension 49 which is adapted to fit within 20 the hollow end 30 of the head 25 and has a pin 50 which enters the slot 31 in said end. The ring 38 has a hollow extension 51 which fits within a hollow hub end 52 of a horn 53, said extension 51 also having a pin 54 25 which is adapted to enter either of two notches 55 and 56 in the hub end 52 of the horn 53.

A second horn 57 has a hub end 58 having a pin 59 thereon, said hub end being adapted 30 to fit within the end portion 29 of the head 25 so that its pin 59 can engage either of the slots 31 or 32. As illustrated in Figs. 1, 2 and 3, the horns 53 and 57 are substantially vertical so that reproduced sound 35 passing therethrough will be directed upwardly; and in Fig. 4 is shown a position where the horns can be secured in an inclined position so as to deflect the sound forwardly according to the desire of the operator.

As shown in Fig. 10, a hose 60 has a ferrule 61 which is of such diameter as to fit within the opening 33 in the head 25. The inner end 62 of the ferrule 61 extends at 45 a curve intersecting the axis of said ferrule and is arranged to intersect a portion of the sound passing through the head 25 and deflect it through the hose 60.

In the operation of my improved machine, 50 the vibration will be jointly imparted to the respective diaphragms 41 and 42 and the sound produced by the diaphragm vibrations will be respectively induced into the head 25 and the horn 52. The sound waves passing into the head 25 will pass through the horn 57 so that distinct sounds will pass out of the horns 53 and 57. By pivoting the head 25 so that the horns 53 and 57 are located at opposite sides of the pivotal axis 55 or in other words at opposite sides of the pivot bolt 24 there will be a partial balance 60 of weight permitting the excess weight on the side including the sound box, so that the latter will engage the record with sufficient 65 weight to properly hold the needle in en-

gagement with the record. If desired, the horns 53 and 57, as previously stated, can be swung into an angular or inclined position, which would be a suitable position when the record of a voice is being played. 70

To remove the elements from the top of the machine, it is merely necessary to raise the post 18 out of the standard 17 and to unscrew the standard 17 from the plate 16. The horns 53 and 57 can be easily removed 75 from the head 25 and the several parts can be readily stored in a comparatively small space.

The hinge 22 permits the block 20 with the head 25 and horns 53 and 57 thereon to 80 be swung into a position indicated in dot-and-dash lines in Fig. 2. This movement will remove the sound box from the record and the weight of the holes is sufficient to hold the parts in their raised position. 85

While I have described my invention as taking a particular form, it will be understood that the various parts of my invention may be changed without departing from the spirit thereof, and hence I do not limit 90 myself to the precise construction set forth, but consider that I am at liberty to make such changes and alterations as fairly come within the scope of the appended claims.

Having thus described my invention, what 95 I claim as new and desire to secure by Letters Patent is:—

1. The combination in a sound reproducing machine including a turntable, of an arm extending over said turntable; a hollow head pivotally supported between its ends by said arm and extending transversely to the length of said arm above said turntable; a horn supported by said head at one side of its pivot and communicating with 100 the interior of said head; and a sound box supported by said head at the other side of its pivot and communicating with the interior of said head; substantially as described. 105

2. The combination in a sound reproducing machine including a turntable, of an arm; a member movably connected to said arm and swingable upwardly and downwardly above said turntable; a hollow head pivoted to said member so as to swing in the path transversely to the path of swinging movement of said member on the arm; a sound box connected to said head and communicating with the interior thereof; a horn connected 115 to said head and communicating with the interior thereof; and means providing a pivotal support for said arm whereby the latter can be swung in a path substantially parallel with the plane of movement of the turntable; substantially as described. 120

3. A sound reproducing machine including a supporting structure providing a bearing; a post freely pivoted within said bearing; a supporting arm on said post; a block 130

hinged on said supporting arm; a hollow head pivoted between its ends to said block; a horn connected to said head at one side of its pivot; a sound box secured to said head on the opposite side of its pivot; and a pin on said head and adapted to swing into engagement with a portion on said block; substantially as described.

5 5. In a sound reproducing machine, a supporting arm; a cup shape housing on the arm; and a transversely extending sound conducting head pivotally connected to said arm and having a pin extending into said housing for limiting the swinging movement of the head; substantially as described.

10 4. A sound reproducing machine including a supporting structure providing a bearing; a post freely pivoted within said bearing; a supporting arm on said post; a block hinged on said supporting arm; a hollow head pivoted between its ends to said block;

15 a horn connected to said head at one side of its pivot; a sound box secured to said head on the opposite side of its pivot; a

housing; and a pin on said head adapted to enter said housing and engage on opposite sides thereof; substantially as described.

20 5. In a sound reproducing machine, a supporting arm; a cup shape housing on the arm; and a transversely extending sound conducting head pivotally connected to said arm and having a pin extending into said 25 housing for limiting the swinging movement of the head; substantially as described.

In testimony whereof I have signed my name to this specification in the presence of two subscribing witnesses.

FRANCESCO CIRELLI.
